(57) **CLAIM**

The ornamental design for display screen or portion thereof with transitional graphical user interface, as shown and described.

DESCRIPTION

FIG. 1 is a front view of the first image in a sequence of a display screen or portion thereof with transitional graphical user interface, showing our new design in a first embodiment;

FIG. 2 is a front view of the second image thereof;
FIG. 3 is a front view of the third image thereof;

FIG. 4 is a front view of the first image in a sequence of a display screen or portion thereof with transitional graphical user interface, showing our new design in a second embodiment;

FIG. 5 is a front view of the second image thereof; and,
FIG. 6 is a front view of the third image thereof.

The appearance of the transitional graphical user interface sequentially transitions between the images shown in FIGS. 1-3 and 4-6. The process or period in which one image transitions to another forms no part of the claimed design. The broken lines showing the display screen or portion thereof in FIGS. 1-3 and the alternate display screen or portion thereof in FIGS. 4-6 form no part of the claimed

(Continued)

design. The remaining broken lines show portions of the transitional graphical user interface that form no part of the claimed design.
